UNITED STATES PATENT OFFICE

LADISLAS TURCHANYI, OF SASHALOM, NEAR BUDAPEST, HUNGARY, ASSIGNOR TO HUNGARIAN RUBBER GOODS FACTORY LIMITED, OF BUDAPEST, HUNGARY, A CORPORATION OF HUNGARY

DESIGN FOR A TOY

Application filed February 21, 1931, Serial No. 38,762, and in Great Britain December 15, 1930.

Term of patent 7 years.

To all whom it may concern:

Be it known that I, LADISLAS TURCHANYI, a citizen of the Kingdom of Hungary, residing in the village of Sashalom, near the city of Budapest, Hungary, have invented a new, original, and ornamental Design for Toy, of which the following is a specification, reference being had to the accompanying drawing forming a part thereof.

The drawing shows a perspective view of one side of a toy embodying my new design, the opposite side being the same as and equivalent to the side here shown.

I claim:

The ornamental design for a toy substantially as shown and described.

LADISLAS TURCHANYI.
